(57) **CLAIM**

The ornamental design for a motorcycle wheel, as shown and described.

DESCRIPTION

FIG. 1 is a front elevational view of a motorcycle wheel showing our new design;

FIG. 2 is a rear elevational view thereof;

FIG. 3 is a left side elevational view thereof;

FIG. 4 is a top plan view thereof;

FIG. 5 is a bottom plan view thereof;

FIG. 6 is an end view taken along line 6—6 in FIG. 1;

FIG. 7 is an end view taken along line 7—7 in FIG. 1; and,

FIG. 8 is a perspective view thereof.

A right side elevational view is a mirror image of FIG. 3.
